MEANS FOR RELEASEABLY AND ADJUSTABLY
CONNECTING A ROTATABLE PIVOT TO A
STATIONARY PIVOTCharles Imhof, Zurich, Switzerland, assignor to
Walter J. Currie, New York, N. Y.Application May 15, 1950, Serial No. 162,015
In Switzerland November 24, 1948

1 Claim. (Cl. 248—279)

1

The present invention relates to a device for mounting upon a stationary pivot, releasably and so that it can be secured in any position, a rotatably supported pivot which may extend transversely thereto.

According to the invention a housing is rotatably mounted on the stationary pivot; a cap or head-piece is so mounted on the housing as to be rotatable about an axis transverse to that of the stationary pivot; in this head-piece a pivot is so mounted as to be rotatable about an axis transverse to the axis of rotation of the head-piece; in the housing there is a screw by means of which clamping pressure can be applied to the stationary pivot to prevent the housing rotating about that pivot; and means are provided for transmitting the clamping pressure at the same time to the rotatable pivot, and to the head-piece, thereby preventing the rotatable pivot from rotating relatively to the head-piece, and preventing the head-piece from rotating relatively to the housing.

The idea of the invention admits of being employed with particular advantage on metal-working and wood-working vises, more especially for watch-makers, opticians and precision-tool workers.

One form of construction of the invention, as applied to a vise, is illustrated by way of example in the accompanying drawings, in which:

Figures 1 and 2, respectively, show partly sectional side and front views of a vise and its mount, as indicated by the viewing lines 1—1 on Figure 2 and 2—2 on Figure 1;

Figure 3 shows in perspective, and partly in section, a detail of the apparatus; and

Figure 4 is a perspective view of the vise.

In the embodiment illustrated, the vise comprises a holder 1, which can be secured to a work-bench by means of a screw spindle 2. The holder 1 has a horizontal bore 3, in which a stationary pivot 4 is non-rotatably inserted. Upon the pivot 4 a housing 5 is rotatably mounted, in which a disc 6, acting as a pressure-piece, is slidable transversely to the pivot 4. By means of a screw 8, engaging in an internal thread in the lower end of the housing, clamping pressure can be exerted upon the stationary pivot 4, thereby preventing the housing rotating relatively thereto, through said pressure piece 6, which slides axially along the housing, and is provided with a recess of cylindrical curvature in its upper surface, in which the pivot 4 engages.

In the upper end of the housing a cap or head-piece 20 is so mounted that it can rotate about

an axis perpendicular to that of the stationary pivot; and in the head-piece a pivot 11 is so mounted that it can rotate about its axis, which is perpendicular to that of the head-piece. A composite pressure-piece consisting of a disc 9 slidable in the housing and a pin 10 extending into the head-piece 20, is interposed between the stationary pivot 4 and the rotatable pivot 11, so that the clamping pressure is further transmitted to this pivot, thus preventing it from rotating relatively to the head-piece. The pressure-piece 9 is provided with a part-cylindrical recess in its under surface, into which the pivot 4 fits. The pin 10 is provided with a part-cylindrical recess in its top surface, into which the pivot 11 fits. An external flange 18 at the lower end of the head-piece 20 engages an internal flange 19 at the upper end of the housing 5, so that when the clamping pressure of the screw 8 forces the pivot 11 upwards it tends to push the head-piece out of the housing, thus pressing the flange 18 against the flange 19, and preventing rotation of the head-piece in relation to the housing. Hence whatever is secured to the pivot 11 can be swung completely around any one of three different axes, and can be held fast in any desired position and orientation by simply tightening the screw 8.

In the constructional example illustrated, the pivot carries one jaw 12 of a vise. To the other jaw 13 is rigidly connected a sleeve 17, which slides upon a pin 16 secured to the jaw 12. The jaw 13 is adjusted relatively to the jaw 12 by means of a screw spindle 14, actuating a sleeve nut 15 upon which the jaw 13 is mounted.

The heads of the screws 2, 8 and 14 may conveniently be made of the same dimensions, so that they can all be adjusted by means of one and the same spanner.

A vise thus mounted may advantageously be employed as a work-holder for milling, planing and boring machines and in other machine tools, as a work-piece once clamped in the vise can be machined on all sides without unclamping and reclamping, thus saving time and minimising indentations such as a vise is liable to make in the work.

Such a vise is also useful in setting-up, welding, riveting and other work in which two articles are required to be temporarily held in any desired positions relatively to one another.

After loosening the screw 8, the vise, together with the rotatable pivot 11, can be readily withdrawn from the head-piece 20, and utilised separately as a screw clamp or a clamping device in any other operation, and the supporting hous-

ing 5, together with the head-piece and pressure-pieces, can be readily withdrawn from the stationary pivot 4, which is permanently secured to the holder 1; and the housing and head-piece, with or without the vise, can be employed separately for certain purposes and fitted to any machine.

I claim:

A bracket for supporting an article for angular adjustment about three axes, said bracket comprising a housing mounted so as to be capable of rotation on a stationary pivot securable to a supporting structure, a head piece mounted so as to be capable of rotation in the housing, the head piece being formed with a transverse cylindrical aperture for the accommodation of a rotatable pivot projecting from the article to be supported, means such as a clamping screw and two pressure pieces in the form of discs slideable in the housing, the discs being co-axial with the clamping screw and formed with transverse hollows of cylindrical curvature to engage the cylindrical surface of the stationary pivot for clamping the housing in any desired angular position into which it may be turned about the stationary pivot, a pin extending into the head piece and having one end in contact with one of said

discs, said pin having a cylindrically curved hollow at its other end which bears against the rotatable pivot to transmit to the rotatable pivot the clamping pressure and thereby secure the latter against rotation in the head piece, and means such as a flange on the lower end of the head piece engaging a flange on the upper end of the housing for transmitting the clamping pressure to the head piece and the housing and thereby securing the head piece against rotation in the housing.
